MULTI-SPEED GOVERNORS

Herman G. Adler, Detroit, Mich., assignor to Continental Motors Corporation, Muskegon, Mich., a corporation of Virginia

Filed Aug. 29, 1960, Ser. No. 52,422
6 Claims. (Cl. 192—084)

This invention relates to governors and more particularly to a multi-speed controlling device for internal combustion engines or other power plants operated at different controlled speeds.

It is generally preferable to employ a speed sensing device such as a fly ball unit in which the centrifugal force is balanced at the required speed, by a spring or other similarly acting means. It is well known that the energy developed by such devices varies as the square of the speed, and directly as the radius of gyration of its rotating masses. Thus when the speed is reduced by say fifty per cent, the energy output is reduced to twenty-five per cent, and is generally insufficient to provide as good a control at the reduced speed as it does at the higher speed.

It is an object of the present invention to eliminate the above mentioned difficulties by providing a multispeed controlling device which operates with the same efficiency at widely different controlled engine speeds.

More particularly, such operation is obtained by constructing a mechanism including any fly ball unit and a rotating actuator shaft therefor and means for operating said shaft at substantially the same speed for widely different controlled engine speeds.

For a more detailed understanding of this invention, reference may be had to the accompanying drawings illustrating a preferred embodiment thereof, like parts being identified by like reference characters throughout the several views, and in which

FIG. 1 is a sectional view through the governor,

FIG. 2 is an enlarged fragmentary sectional view on the line 2—2 of FIG. 1,

FIG. 3 is a sectional detail view taken on the line 3—3 of FIG. 1,

FIG. 4 is a fragmentary sectional view of the governor showing same as operable at the low engine controlled speed as hereinafter described, and

FIG. 5 is a general assembly, partly diagrammatic.

The present invention is illustrated as embodied in a hydraulic governor equipped with a pressure regulating means described in my prior Patent No. 2,733,690, issued Feb. 7, 1956, but it will be obvious that my invention may be utilized to directly operate an external lever of a conventional type mechanism connected mechanically to a carburetor throttle whereby to control engine speed.

The hydraulic governor illustrated herein is substantially like the structure described and claimed in my prior Patent No. 2,733,690 issued Feb. 7, 1956, and a brief description is hereinafter set forth:

Referring now to the drawings, the governor comprises a main casting 10 having a generally cylindrical recess 12 therein closed by a removable cap 14 and containing a piston 16. At one side of the piston 16 is compression spring 18 which seats against the inner end of the cylinder and bears against the piston. The cap 14 has an opening 20 therethrough which receives the piston rod 22, suitable sealing and guide means for the piston rod being indicated at 24. The outer end of the piston rod 22 is connected to a lever 26 which is appropriately connected to the throttle of an internal combustion engine. For a detailed disclosure of the connections between the piston rod 22 and the lever 26, reference is made to my prior Patent No. 2,745,384, issued May, 15, 1956.

The present governor operates by utilizing lubricating

2

oil supplied under pressure by the usual oil pump provided on the governed engine. In order to maintain uniform operating characteristics for the governor throughout possible wide changes in pressure and temperature of the lubricating oil, means are provided in the present governor for regulating oil pressure at a value for which the governor is designed.

The pressure regulating mechanism is built into the main casting 10 of the governor, the casting being provided with a projecting portion 28 having a generally cylindrical recess 30 formed therein. The recess 30 is adapted to be closed at its otherwise open end by a removable cap 32. Located intermediate the ends of the cylinder 30 is a lateral annular enlargement 34 which forms an annular chamber. A pair of cylindrical sleeves 36 and 38 are provided in the cylinder 30, the sleeves 36 and 38 being axially aligned and spaced apart such that their adjacent end surfaces 40 and 42 respectively define an annular port 44.

20 Located within the sleeves 36 and 38 is a spool valve 46 having lands 48 and 50 slidably respectively in the sleeves 36 and 38. The valve 46 is provided with a reduced portion 52 intermediate the lands 48 and 50. A passage 54 is provided in the body which as best seen in FIG. 2, is lune shaped. The passage 54 communicates with a closed space 56 so that the pressure of fluid in the annular chamber 34 is effective on the left hand end of the valve 46, as seen in FIG. 1.

30 The valve 46 has a recess 58 open at one end and extending substantially the entire length of the valve. A pressure regulating spring 60 is provided, the main portion of the spring being received within the recess 58. The ends of the spring seat respectively at the right hand end of the cylinder, as seen in FIG. 1, and at the closed end of the recess 58 in the valve. The right hand end of the cylinder 30 is provided with a shallow seat 62 and a similar seat 64 is provided at the inner closed end of the valve. By this construction the spring 60 is prevented from buckling and accordingly a relatively long spring may be employed which is desirable for pressure regulation.

40 Hydraulic fluid is supplied through an inlet opening 66 which extends from the exterior of the casting 10 into the space between the intermediate reduced portion 52 of the valve and the adjacent inner surface of the sleeve 38. An outlet passage 68 connects the chamber 34 to speed responsive control valve mechanism which will now be described.

45 The casting 10 includes an open recess 70 in which is received centrifugal mechanism indicated generally at 72. Operatively connected to the centrifugal mechanism 72 is a spool valve 74 slidably in a sleeve 76 and adapted to control the flow of fluid from the passage 68 to a passage 78 which communicates with the cylinder 12 intermediate the piston 16 and the cap 14. Details of the valve mechanism may be as disclosed in my prior patent identified above.

50 Extending from the passage 78 is a small bleed passage 80 which is best shown in FIG. 3, which communicates with a second passage 82 which is provided with a needle valve 84 adapted to be adjusted by an adjusting screw 86 to control leakage flow of fluid. The purpose of this is to insure a relatively small but definite flow of oil through the governor at all times.

55 Referring again to FIG. 1 it will be observed that the left hand end of the valve 46 has a flat end surface 90, and the removable cap 32 is provided with an abutment 92, the end of which has an area adapted to fit in surface-to-surface contact with the flat end surface 90 of the valve. 60 The abutment 92 is designed to limit movement of the valve to the left as seen in FIG. 1, to a position such that

the inner edge of the land 48 coincides with the edge 49 of the sleeve 36. In other words, when the valve is in the extreme left hand position, as seen in FIG. 1, its end surface 90 engages the abutment 92, and the annular port 44 is in fully open position. In addition, the provision of the cooperating surfaces at the end of the valve and on the abutment 92 serve an additional function. When the engine is initially started, the valve 46 will be in the extreme left hand position due to the action of the spring 60. At this time the engine may have been idle for some time or lubricating oil may have somewhat congealed or stiffened. As the pressure of the lubricating oil builds up, the pressure applied to the valve in the space 56 is applied to less than the entire end area of the valve, due to the surface-to-surface contact between the area 90 and the valve and the cooperating surfaces 90 and 92. For this purpose, of course, surfaces 90 and 92 are accurately finished to prevent entrance of pressure fluid therebetween. Thus, the pressure required to overcome the spring 60 will exceed the desired regulated pressure by a definite amount. In the example illustrated, the area of the surface 90 constitutes approximately one-eighth of the entire area at the end of the piston, and accordingly the pressure initially required to overcome the spring 60 will be from ten to twelve percent above the desired regulating pressure. Upon the first slight movement of the valve 46, this pressure will be effective to move the valve abruptly and will thus free the valve for subsequent movement. The action may be likened to mechanically moving the valve 46 to free the valve for subsequent automatic operation.

In addition, this last arrangement provides oil to the governing mechanism at a pressure somewhat in excess of the normal governed pressure upon initial starting of the engine and in some cases this additional pressure may be advantageous in preventing running the engine up to an excessive speed upon first starting the engine.

The speed sensing element 72 is a fly ball unit in which the centrifugal force is balanced at the required speed by a spring 100. In order that the energy output and adjustment of the centrifugal unit at low speed may be the same as it is at high speed, it is necessary that the speed of the centrifugal unit at low engine speed is the same as it is at high speed. This is accomplished by employing a drive mechanism provided with a gear arrangement that has a gear ratio which steps up the speed of the centrifugal unit, and which is only operable at low engine speed.

Again referring to FIG. 1, the shaft 101 is driven by a power plant (not shown) such as an internal combustion engine or other equivalent energy producing machine. Such machine or engine is provided with a conventional speed control means actuated by the lever 26.

The speed of shaft 101 is always directly proportional to the speed of the machine or engine and the drive shaft 102 is rotatably mounted within longitudinal bore 102a of shaft 101 and gear 103 is pressed onto or otherwise suitably secured or attached to the drive shaft 102. The shaft 101 is provided with a counterboard recess 104 and gear 103 is provided with two cammed surfaces which form converging passages when gear 103 is assembled as shown with shaft 101. A ball 105 is assembled in each of these converging passages, thus forming an overrunning clutch providing a unidirectional drive. Thus shaft 101 will drive the centrifugal unit drive shaft 102 through balls 105 and gear 103, but should the speed of shaft 102 exceed the speed of shaft 101, the balls 105 will move into the diverging portion of the converging recesses formed by the cammed surfaces, and permit shaft 102 to rotate freely within the shaft 101.

The above mentioned shaft 102 is supported in casing 10A bolted or otherwise secured to casing 10, and said casing 10A rotatably supports the layshaft or counter-shaft 106 in suitable bearings. A gear 107 is secured on the layshaft 106 and is in constant mesh with the integral gear portion 101a of shaft 101. Since gear 107 is smaller

in diameter than gear 101a, the speed of layshaft 106 is always higher than that of shaft 101. The gear 108 is rotatably mounted on the layshaft 106, being supported on the anti-friction bearing 109. The gear 108 is in constant engagement with gear 103, and since its diameter is larger than that of gear 103, its speed is always lower than the speed of the centrifugal unit drive shaft 102.

The layshaft 106 is provided with a pair of flat surfaces 106a machined on diametrically opposite sides, and clutch plates 109a are provided with openings or holes with oppositely flat sides fitting snugly over the flattened portion of shaft 106, and consequently are driven by shaft 106 and always rotate therewith.

Gear 110 is rotatably mounted on layshaft 106 and is disposed or located between the clutch plate 109a, and this gear 110 is also in constant mesh with gear 103. Likewise the diameter of gear 110 is the same as gear 108. A collar or flanged sleeve 111 is slidably mounted on the layshaft 106 and a thrust bearing 112 is mounted between the collar and the adjacent clutch plate 109a.

An actuating forked lever 119 is pivotably mounted on casing 10A by means of stud shaft 113 to which the forked lever is pinned or otherwise suitably secured. Actuation of stud shaft 113 counterclockwise as seen in FIG. 1, will move said forked lever to the right and engage the surfaces between gear 107 and gear 108, between gear 108 and the adjacent plate 109a, between the aforesaid plate 109a and gear 110, thus becoming frictionally engaged and forced to all rotate together at the same speed as said layshaft 106, and thus will in turn cause the shaft 102 to rotate faster than shaft 101 as gear 103 is in mesh with gears 108 and 110.

The ratio of these gears 101a, 107, 108 and 103 are so selected, that the speed of the centrifugal unit drive shaft 102, at the lower controlled engine speed, is the same as it is at the higher controlled engine speed, provided that sufficient pressure is applied to the sliding collar 111 to clutch the gears 108 and 107 at the lower controlled engine speed and that such pressure is removed at the higher controlled engine speed. In short, the gears 107 and 108 are clutched at said lower engine speed and declutched at said higher engine speed. Actually the movement of the clutch collar 111 is very slight, since all that it does is to take up the exceedingly small clearances between the elements of the disc type clutch as heretofore described.

Obviously, the shaft 113 to which is attached the forked lever 119 for actuating the aforesaid clutch device, may be actuated by any suitable means, manually or automatically if so desired.

In FIG. 5, I have shown an assembly, somewhat diagrammatic of an assembly showing an engine "A" on which the above described multi-speed governor is mounted, an auxiliary machine "B" which can be drivingly clutched, to a power output shaft "C" of said engine, a switch "S" or other suitable means, which when turned to "On" position will close the electrical circuit and actuate a clutch actuating device "D" to clutch the auxiliary machine "B" to said engine. This electric circuit "E" including a battery F may close the circuit to a solenoid 115 and operate the solenoid to actuate said shaft 113 as desired.

When the solenoid 115 is energized on closing of switch "S," the solenoid armature 120 is pulled, comprising the spring 121 and the rod 122 attached to lever 123 is moved downwardly as shown, causing the shaft 113 to rotate in a counterclockwise direction an amount to apply sufficient pressure to clutch gears 107 and 108. Thus the pressure applied to the clutch collar 111 is determined by the compression in spring 121 rather than by the pull on armature 120. The switch "S" which operates solenoid 115 may be arranged to be automatically closed by a suitable connection with the clutch device D, so that when the auxiliary machine B is clutched to the engine A, the switch is closed, and is opened to de-energize the

solenoid when the auxiliary machine is de-clutched from said engine A.

As noted, the engine is governed at a relatively higher controlled speed when operating to drive a vehicle, but is operated at a relatively lower controlled speed when clutched to the auxiliary machine which may be a pump or other auxiliary equipment. The present invention provides a construction in which the speed of the centrifugal unit is the same at both high and low controlled engine speeds, so no change in the adjustment of the 10 governor spring is required.

It will be apparent to those skilled in the art to which my invention pertains that various changes and revisions of the elements described herein may be made without departing from the spirit of my invention or from the 15 scope of the appended claims.

I claim:

1. In an engine adapted for driving machinery at a lower than normal operating engine speed, means selectively drivingly connecting said engine with said machinery, said engine having a speed control device, a governor having a speed responsive actuator normally operable to adjust said speed control device over a predetermined range of speed of said engine, control means operable on connecting said engine with said machinery to automatically vary the operation of said speed responsive actuator to effect adjusting of said speed control device over a lower range of speed of said engine, and including driving means operably connecting said engine with said 20 governor, said driving means including an overrunning clutch and transmission gear mechanism operably to vary the speed of said speed responsive actuator.

2. In an engine adapted for driving machinery at a lower than normal operating engine speed, means selectively drivingly connecting said engine with said machinery, said engine having a speed control device, a governor having a speed responsive actuator drivingly connected to said engine and normally operable to adjust said speed control device over a predetermined range of speed of said engine, control means operable on connecting said engine with said machinery to automatically increase the 25 speed of said speed responsive actuator to effect adjusting

of said speed control device over a lower range of speed of said engine.

3. A multi-speed governor for an engine adapted for driving machinery at a lower engine speed than for normal operation, said engine having a rotating part and being selectively operated at at least two different controlled speeds, said governor comprising a speed responsive device having an actuator shaft, means for connecting said shaft to said engine rotating part and including an overrunning clutch, and a second means comprising transmission mechanism for driving said shaft at substantially the same speed from said engine rotating part operating at a slower speed for controlling engine operation at the lower controlled speed, means selectively drivingly connecting said engine with said machinery, and control means operable on connecting said engine with said machinery, to automatically engage said rotating engine part to said shaft through said transmission gearing.

4. A multi-speed governor as defined in claim 3 20 wherein said transmission gear mechanism embodies a shiftable clutch normally disengaged to permit said direct drive of said shaft by the engine rotating part, and means actuating said transmission clutch on clutching said engine to drive said machinery.

5. A multi-speed governor as defined in claim 4, 25 wherein said transmission clutch actuating means comprises a solenoid actuated lever, and a switch controlling the operation of said solenoid, said switch automatically actuated on clutching said engine to said machinery.

6. A multi-speed governor as defined in claim 5 30 wherein a spring is interposed in the connection between said solenoid and transmission clutch to transmit the energy of solenoid movement to the spring whereby to apply spring pressure only to said clutch for actuating same.
